UNITED STATES PATENT OFFICE.

HARRY J. THOMPSON, OF SAN FRANCISCO, CALIFORNIA, ASSIGNEE TO NATIONAL FIBREFORM COMPANY, OF SAN FRANCISCO, CALIFORNIA.

PACKING SHEET FOR GLASS JARS AND THE LIKE.

Application filed February 11, 1922. Serial No. 535,834.

To all whom it may concern:

Be it known that I, HARRY J. THOMPSON, a citizen of the United States, residing at San Francisco, in the county of San Francisco and State of California, have invented a new and useful Packing Sheet for Glass Jars and the like, of which the following is a specification.

This invention relates to packing sheets 10 designed primarily for use in holding glass jars while in transit or while being handled in quantities so that they will not be broken through rough handling.

One of the objects of the invention is to 15 provide packing sheets or trays of novel form designed to act as cushions and also as spacing means for holding the jars or the like properly positioned at all times.

A further object is to provide packing 20 sheets preferably formed of paper pulp molded to proper shape and capable of being assembled readily for the purpose of properly positioning the jars or other articles therebetween.

Another object is to provide packing 25 sheets which can be disposed in superposed relation so that several layers or groups of jars or similar articles can be packed in one create or container without being injured.

With the foregoing and other objects in 30 view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a plan view of a portion of one of the packing sheets.

Figure 2 is a section on line 2—2, Figure 1.

Figure 3 is a section on line 3—3, Figure 1.

Figure 4 is a section showing two superposed oppositely arranged packing sheets with a jar held therebetween.

Figure 5 is a view on a reduced scale similar to Figure 4 but showing an interposed or intermediate packing sheet combined with the top and bottom sheets.

Figure 6 is a plan view of the intermediate packing sheet.

Figure 7 is a section on line 7—7, Figure 6.

Referring to the figures by characters of reference 1 designates a molded sheet preferably formed of paper pulp, this sheet being formed at desired intervals with depressed portions constituting seats 2 so proportioned as to receive, for example, the bottoms of jars to be packed. As shown in Figure 2 the bottoms of the seats 2 are preferably rounded to conform with the contour of the bottoms of the jars to be placed therein. Furthermore the walls between the seats are depressed, as shown at 3 thus to provide connecting ribs between the seats to reinforce or stiffen the sheet between the seats. As the entire sheet is molded of paper pulp or a like porous substance the recessed face 70 thereof will present a smooth finished appearance but the opposed face of each sheet is preferably rough and unfinished as clearly indicated in Figures 2 and 3. This unfinished or rough surface provides numerous 75 projections or nodes some of which have been indicated at 4 whereby when two sheets are placed back to back the said nodes act as cushioning means to absorb shocks not otherwise absorbed by the structure of each of the sheets.

All of the sheets can be similarly made, it being designed to arrange them in pairs, the upper sheet of each pair being inverted as shown in Figure 4 so as to receive the top 80 portions of the jars carried by the lower sheet. In Figure 4 one of the jars has been indicated at J. Obviously if articles other than jars are to be used the upper sheet of each pair would have to have seats therein 85 so shaped and proportioned as properly to fit the upper ends of the articles mounted on the lower sheet. Where both ends of the held article are of approximately the same diameters, however, only one style of 90 packing sheet need be used.

After one group of jars or similar articles has been positioned between two sheets as shown in Figure 4, another pair of sheets 105 with jars or the like therebetween can be placed thereabove as will be obvious. It is of course to be understood that all of these packing sheets with the articles therebetween can be placed within a suitable container and that after the articles have thus been located 110

the container can be transported from place to place and subjected to rough handling with little danger of injuring the contents of the container.

- 5 Under some circumstances it is desirable to protect the intermediate portions of the held articles and for this purpose an intermediate packing sheet such as shown at 5 in Figures 5, 6 and 7 can be used. This sheet 10 is likewise formed of paper pulp or the like and is made quite thick so as to span the space between the top and bottom packing sheets engaging the articles. Openings 6 are 15 formed within the intermediate sheet 5 and are proportioned to receive the intermediate portions of the held jars or other articles. With parts assembled as shown in Figure 5 the danger of breakage is almost entirely 20 eliminated.
- 20 While paper pulp is preferably used in the formation of the packing sheets it is to be understood that these sheets can be molded from any other fibrous material if desired provided said material has the cushioning 25 and protective properties of paper pulp.

What is claimed is:—

1. A structure of the class described including oppositely disposed packing sheets each formed of fibrous cushioning material 30 molded and having spaced depressions there-

in, the depressions in one of the sheets constituting seats for the lower ends of articles to be packed and the depressions in the other sheet constituting seats for the upper ends of the said articles, the said sheets being spaced apart, and an interposed protecting sheet of fibrous cushioning material bridging the space between the upper and lower packing sheets and having openings therein in which are seated the intermediate portions of the packed articles. 35 40

2. A structure of the class described including oppositely disposed packing sheets of fibrous cushioning material molded and having opposed recesses therein constituting seats for the opposed ends of articles therebetween, said sheets being spaced apart, and an intermediate sheet constituting spacing means between the first named sheets and having openings therein through which the 45 packed articles extend, said intermediate sheet being formed of fibrous cushioning material. 50

In testimony that I claim the foregoing as my own, I have hereto affixed my signature in the presence of two witnesses. 55

HARRY J. THOMPSON.
